(57) **CLAIM**

The ornamental design for a tool handle, as shown and described.

DESCRIPTION

FIG. 1 is a perspective view of a tool handle in accordance with the present invention;

FIG. 2 is a first side elevational view of the tool handle; a second side elevational view of the tool handle is a mirror image of the first side elevational view;

FIG. 3 is a top plan view of the tool handle;

FIG. 4 is a bottom plan view of the tool handle; and,

FIG. 5 is a front elevational view of the tool handle; a rear elevational view of the tool handle is a mirror image of the front elevational view.
